Primary Examiner — Cathron C Brooks(74) *Attorney, Agent, or Firm* — Barley Snyder(57) **CLAIM**

The ornamental design for a quilted hammock, as shown and described.

DESCRIPTION

FIG. 1 is a front, top and right side perspective view of a quilted hammock, showing the new design;

FIG. 2 is close-up front, top and right side perspective view of the quilted portion in FIG. 1;

FIG. 3 is a top plan view thereof;

FIG. 4 is a front elevation view thereof;

FIG. 5 is a rear elevation view thereof;

FIG. 6 is a left side elevation view thereof;

FIG. 7 is a right side elevation view thereof; and,

FIG. 8 is a bottom plan view thereof.

The broken lines shown in the drawings are included for the purpose of illustrating environmental structure and form no part of the claimed design.

1 Claim, 6 Drawing Sheets(56)
